United States Patent Office

Des. 206,538
Patented Dec. 27, 1966

206,538

BOOK RACK

Peter R. Hollaender, Cincinnati, Ohio, assignor to The Hollaender Manufacturing Company, Cincinnati, Ohio, a corporation of Ohio

Filed Oct. 4, 1965, Ser. No. 87,303

Term of patent 14 years

(Cl. D33—3)

FIG. 5

I claim:

The ornamental design for a book rack, substantially as shown.
